PUMPING EQUIPMENT

Wilbur J. Crites, Bartlesville, Okla., assignor to
Phillips Petroleum Company, a corporation of
Delaware

Application September 18, 1939, Serial No. 295,523

1 Claim. (Cl. 74—41)

This invention relates to improvements in pumping machinery used in the production of oil from wells, and particularly, to the equipment employing an electric motor as a prime mover of such machinery.

In pumping oil from wells it is the most common practice to employ what is known as the sucker rod type of pump. These pumps have a piston disposed in a pump barrel at the lower end of the well, and a string of sucker rods extending upwardly to a reciprocating device at the upper end of the well. In pumping deep wells, the weight of the rod string is of considerable magnitude and as a consequence, must be counter-balanced by a number of weights on the reciprocating pumping equipment at the upper end of the well. Counter-balancing in this manner tends to balance the load on the driving motor and decrease the variation between the amount of power required in lowering the rod string and the amount of power required to raise the rod string together with the oil being pumped. Two factors which prevent an even power requirement during the entire cycle of raising and lowering are the elasticity of the rods and the compressibility of the fluid being produced by the well. As a consequence, power requirements during one cycle of the pumping of a deep well vary over a wide range despite the effect of counterbalancing.

In the application of electric motors to the pumping of beam operated wells, it has been an accepted practice to install electric motors of a rated power capacity fifty percent in excess of the power required to pump the well by a gas engine loaded to its full capacity. Attempts were made to install electric motors of the same rated power capacity as was required when using gas engines, with the result that the electric motors showed excessive heating and other symptoms of being overloaded. In making an analysis of this problem, a dynamometer chart was used and it was apparent that the electric motor did not have sufficient power to carry over the peak load imposed upon it at some time during the rise of the pumping rods. A further analysis showed that at other times during the pumping cycle the motor was not called upon to deliver its full rated horsepower. During the light load periods, the motor attained synchronous speed and at times was even driven beyond synchronous speed. Any energy imparted to the motor by the pumping unit was not stored up in the motor itself, but was converted into electrical energy and dissipated through the power

transmission lines. In analyzing the characteristics of a gas engine application to the pumping unit, it was found that energy imparted to the gas engine by the pumping unit was converted into kinetic energy of the flywheel and was stored as kinetic energy within the flywheel until needed during the peak load on the pumping equipment.

The present invention proposes to apply a flywheel to an electric motor installation to store up kinetic energy during periods of slack loads on the pumping equipment and to utilize this energy during peak loads on the pumping equipment to assist the motor in carrying over the peak loads without overloading the motor. The application of a flywheel to electric motor driven well pumping equipment was successfully carried out in an installation in an oil field in the State of Arkansas. It was found preferable to use a flexible coupling between the flywheel and the pumping equipment to prevent shock loading on the pumping equipment and the driving motor during the peak load period. Application of a flywheel in this manner has proven successful in these pumping operations and has resulted in many advantages.

The advantages attained by the application of this invention are:

Decreased cost of pumping equipment. By application of a flywheel, the rated power capacity of the electric motor installed may be equivalent to the rated power capacity of a gas engine required to pump the same well. This means a decrease in rated motor power capacity of about thirty percent over the usual practice in installing electric motors which in turn means a decrease of about fifty percent in the cost of the electric motor used. The increased cost due to the flywheel and flexible coupling is negligible in comparison to the decrease in the cost of the electric motor used.

Decreased operating expenses. Operating expenses are decreased since the motor is not overloaded and therefore not subject to excessive current consumption or overheating. Actual operation in the Arkansas field showed that the application of a flywheel and flexible coupling to an electric motor installation effected an overall efficiency increase of two and one-half percent and reduced the operating temperature of the motor thirteen degrees. This means a longer life for the motor as well as a saving in current consumption.

Longer life of pumping equipment. The energy stored in the flywheel is transmitted to the

pumping equipment during peak loads through the flexible coupling means which protects the equipment from shock loads, increasing the life of the equipment and especially the life of the sucker rods which are liable to fatigue failure.

An object of this invention is to provide pumping equipment for oil wells which may be efficiently driven by an electric motor.

A further object of the present invention is the application of a flywheel to pumping equipment to assist the prime mover over periods of peak loads.

A still further object of the present invention is to provide a flywheel and flexible coupling means to pumping equipment to reduce stresses and shock loading in said equipment.

Other objects and advantages of the present invention will be apparent from the following description and the accompanying drawing forming a part of this specification.

Figure 1 is a plan view of a pumping unit embodying a preferred form of the present invention.

Fig. 2 is an elevation view of the pumping unit shown in Figure 1.

In the drawing where like numerals designate similar parts, the numeral 4 represents the prime mover of a pumping unit for which I prefer to use an electric motor of high slip characteristics. Rotary motion developed by motor 4 is transmitted by shaft 5 to a flywheel 6 and to one-half of a coupling means 7 connected thereto. A pulley 8 is connected to the other half of coupling means 7 which is so constructed and arranged as to allow a pre-determined amount of slippage or flexibility between pulley 8 and shaft 5. V-belts 9 transmit power from shaft 5 to drive wheel 10 which is connected to pitman 11. Pit-

man 11 is connected at one end to the walking beam 12 which is supported by the Samson post 13.

In operation, the prime mover 4 is set in motion and its motion transmitted through shaft 5, coupling means 7, pulley 8, and belts 9 to drive wheel 10 to which the pitman 11 is attached. The pitman actuates walking beam 12 and reciprocates the polished rod in the well to effect pumping of oil from the well. Flywheel 6 is set in motion by prime mover 4 through means of shaft 5. Kinetic energy stored in the flywheel during slack periods is utilized during peak load periods to assist the motor. Shock to the pumping equipment during peak load periods is prevented by the flexible coupling between shaft 5 and pulley 8.

It is to be understood that the form of my invention, herewith shown and described, is to be taken as a preferred example of the same, and that various changes in the shape, size, and arrangement of parts may be resorted to without departing from the spirit of my invention or the scope of the subjoined claim.

Having thus described my invention, I claim:

In a well pumping unit the combination comprising a walking beam having sucker rods attached to one end thereof and a pitman to the other end, a prime mover to drive the pumping means, a flexible hydraulic coupling between the pitman and the prime mover to absorb impact shocks from the sucker rods, and a flywheel connected to the prime mover to store up energy in the flywheel, said energy being imparted to the flywheel by the downward movement of the sucker rods.

WILBUR J. CRITES.
